United States Patent Office

Des. 191,332
Patented Sept. 12, 1961

191,332

PRINTING MACHINE

John A. Maul, Lyndhurst, and Roy P. Hess, Westlake, Ohio, assignors to Addressograph-Multigraph Corporation, Cleveland, Ohio, a corporation of Delaware

Filed Feb. 10, 1960, Ser. No. 59,339

Term of patent 14 years

(Cl. D64—11)

FIG. 1 is a top perspective view of a printing machine embodying our new design;

FIG. 2 is a front elevational view thereof;

FIG. 3 is a rear elevational view;

FIG. 4 is an end elevational view thereof as seen from the left of FIG. 2; and

FIG. 5 is an end elevational view thereof as seen from the right of FIG. 2.

The dominant features of the design reside in those portions shown in full lines.

We claim:

The ornamental design for a printing machine, substantially as shown and described.
